CLAIM

The ornamental design for a deadbolt knob and door-knob engaging security unit, as shown and described.

DESCRIPTION

FIG. 1 is a top, front, and left side perspective view of a deadbolt knob and doorknob engaging security unit showing my new design;

FIG. 2 is an enlarged rear elevational view thereof;

FIG. 3 is an enlarged left side elevational view thereof;

FIG. 4 is an enlarged right side elevational view thereof;

FIG. 5 is an enlarged top plan view thereof; and,

FIG. 6 is an enlarged bottom plan view thereof.

FIG. 1

FIG. 4

FIG. 3

FIG. 2

FIG. 5

FIG. 6
